COMBINED SHOE POLISH APPLICATOR,
HAND DAUBER, AND BRUSH

Harry M. Schwartz, Baltimore, Md.

Application January 18, 1950, Serial No. 139,269

2 Claims. (Cl. 15—118)

1

This invention relates in general to improvements in hand brushes for polishing shoes, and more particularly to a hand operated combination shoe brush and polisher and fountain-fed shoe polish applicator and dauber for shoes.

An object of the invention is the provision of a shoe polishing set whereby, when once grasped in the hand, a person may apply polish to a dauber, spread the polish over a shoe with the dauber, and then brush the so daubed polish on a shoe to polish the same, at will, all in one grasp of the brush or polisher, thus eliminating the necessity of repeated operations of applying polish from a separate container therefor to a cloth or other dauber, repeated applications of the latter to a shoe, and thence brushing the shoe with a separate brush.

A further object of the invention is to provide a polishing set in which all the essentials for polishing a shoe are contained in one unit, and in a way that avoids smudging of the person's hands, or opening of polish containers, by a person in the course of shining shoes.

A further object of the present invention is the provision of a combined fountain fed shoe polish hand dauber and polisher for shoes in which the polishing pad of the polisher is kept free of contact with the shoe during feed of polish to, and the spreading of the polish by the dauber; and in which the daubing surface is clear of the shoe during brushing and polishing of the shoe, thus avoiding application of polish to the brushed surface of the shoe during brushing, as well as also avoiding smudging of the polishing pad with polish.

Accordingly, the present invention provides for the above purpose, a polisher set having a main body portion in the form of the counterpart of a conventional hand brush or polisher for shoes, the upper portion constituting the back for the brush and providing a handle for grasping in the hand of a person during brushing or polishing a shoe, and the lower portion being constituted of a pad in the form of bristles, felt, chamois, or the like, for brushing and polishing shoes.

At one end of the main body portion there is provided an upwardly and outwardly inclined extension in the form of a dauber head. The dauber head is provided in its upper part with a receptacle for polish preferably in liquid form, together with a removable lid for access to the interior of the receptacle through its top, while on its lower face the dauber head is provided with a daubing surface. A fountain feed mechanism is provided within the head for feeding

2

polish from the receptacle to the daubing surface, so that controlled amounts of polish may be automatically discharged from the receptacle to the daubing surface whenever the dauber pad is pressed more firmly on a shoe than is normally done in spreading polish over a shoe by means of the daubing surface.

In one form of the invention a removable closed container is provided for insertion in the receptacle, in order to provide for easy renewal of the supply of liquid polish to the receptacle in the head. In such case the fountain feed mechanism is arranged to automatically feed liquid polish from the interior of the closed container.

15 With the foregoing arrangement it will be noted that a reserve supply of polish, preferably in liquid form, may be provided in the set, and automatically fed to a dauber in controlled amounts, spread thereby over the surface of a shoe, and 20 the shoe then polished, without the hands of a person ever coming in contact with the polish, or requiring more than a single grasping of the handle of the brush in order to apply, spread, and polish a shoe, by the hand of a person in manually shining shoes.

In so doing, it will be noted that when brushing the shoe the brushed portions of the shoe are not re-daubed with polish by the dauber in the course of polishing, and in daubing the shoe 30 with the dauber, the daubed parts are not brushed by the polishing element of the brush in the course of daubing, thus keeping the brush free of excess polish during the daubing of a shoe and avoiding waste of polish during the brushing of 35 a shoe by the polishing pad of the brush. For this purpose it suffices to have the dauber head inclined relative to the brush, at an angle of about 15°, whereby each lower brush or dauber surface clears the shoe surface when the other is 40 being applied to a shoe for its intended purpose.

The invention has for further objects such other improvements and such other operative advantages or results as may be found to obtain in the structure hereinafter described or claimed.

45 Referring to the drawings:

Figure 1 is a top plan view of the combined shoe polisher and dauber providing the fountain feed features of the present invention;

Figure 2 is a side elevational view partly in 50 vertical longitudinal cross-section on the line 2—2 of Figure 1;

Figure 3 is a transverse vertical cross-sectional view taken on the line 3—3 of Figure 1;

Figure 4 is a sectional view of a modified form 55 of polish container.

To illustrate the preferred embodiment of the invention, there is shown on the drawing a hand operated shoe brush 10 comprising a horizontally elongated, narrow, and generally rectangular, brush back 11 with a brushing pad 12. The brush back 11 forms the handle to be grasped in the hand by a person in operating the brush and has integrally formed therewith at one end of the handle a dauber head 13, which is arranged in the form of an upwardly inclined extension of the back, at an angle of about 15° to the horizontal of the back 11.

The dauber head is provided with a daubing pad 14 on its lower surface, and a receptacle 15 in its upper part for holding a reserve supply of polish, for supply to the pad 14. The receptacle is open at its top and is provided with a lid 16 pivotally mounted at 17 for access to the interior of the receptacle, when released from a latch 18 for holding the lid in tight closing relation over the receptacle.

The dauber head is also provided with a fountain feed mechanism, indicated generally at 19, for automatically feeding controlled amounts of polish, preferably in liquid form, from the reservoir to the region of the daubing pad, under application of pressure of the dauber head, when the daubing pad 14 is pressed more firmly on the shoe, by the hand of a person grasping the handle provided by the brush back 11, than is normally done by the hand when moving the daubing surface 14 over the surface of a shoe in spreading the polish thereon.

In the form shown, the fountain feed mechanism comprises a duct 20 leading from the bottom of the receptacle 15 to the bottom of the dauber head, a valve 21 seating on the mouth 22 of the duct 20 in the receptacle, resilient means 23 in the form of a spring engaging the top of the receptacle and the valve 21, for normally urging the valve in seating relation, and a valve stem 24 extending from the valve through the duct 20 to a region beyond the base of the dauber head, but terminating above the lower surface of the dauber pad, so that upon pressure of the end of the stem 24 on a shoe, the stem 24 is retracted against the action of the spring 23 and unseats the valve 21, whereupon polish, in the receptacle 15 flows therefrom through the duct 20 to the region of the pad 14.

For convenience, and economy in manufacture a single strip 25 of material is used to form both the polishing pad 12 and the dauber pad 14, the strip 25 being secured as by means of glue, or other fastening means to base of the brush back 11 and the base of the dauber head 13. This strip 25 may be felt, chamois, and the like or hair bristles may be employed in place of the other conventional pad material.

The daubing pad portion 14 is provided with a duct 26 in registry with the duct 20 for easy penetration of the end of the stem 24 and of the polish to the outer surface of the daubing pad 14.

In the preferred form of the invention, the polish, especially when in liquid form, is filled into the receptacle 15 in the form of a closed container 27 which may be readily inserted in the receptacle 15, removed and replaced by another in renewing the supply of polish for the receptacle 15. In such case, the container 27 is provided with a removable lid 28 and an aperture 29 in registry with the duct 20 where the latter opens into the receptacle 15, and the spring 23 and valve 21 are then both contained within the container 27 so that the valve 21 may seal off the

aperture 29 under the action of the spring 23. In such case the spring abuts the lid 28 and the stem 24 projects from the valve 21 through the container aperture 29, thence through the duct 20 leading from the receptacle 15, to the duct 26 in the daubing pad 14.

However, it is to be understood that the invention is not to be limited in all its aspects to the specific form of fountain feed mechanism thus shown and described, but that other conventional forms of fountain feed mechanisms may be used which employ the principle of pressure to automatically feed liquid or other material in controlled amounts.

As shown the brush back 11 and dauber head 13 are formed of wood, but they may be formed of other material, such as plastic, metal, or other suitable solid backing material.

In operation, lid 16 is swung on its pivot 17 and a container 27 filled with liquid shoe polish inserted in the receptacle 15 with the stem 24 projecting through the ducts 20, 26, whereupon lid 16 is closed and fastened at 18.

With the person holding the brush by grasping the back 11 in the hand, the brush 10 is tilted to press the dauber pad 14 firmly on different parts of a shoe, thus pressing the stem 24 inwards against the spring 23 in the container 27 and unseating the valve 21.

Upon so doing, liquid polish flows from the container 27 through the duct 20 and out onto the surface of the shoe and daubing pad 14 through the duct 26 in the pad 14.

Then the pressure of the hand is lessened and the brush handle 11 moved in a manner to operate the dauber head 13 in the conventional manner for spreading the polish on the shoe, after which the handle 11 is lowered to bring the brush pad 12 into position for brushing, thus raising the dauber pad 14 away from the shoe surface, and brushing of the daubed area then effected.

When the container 27 is emptied it is replaced by another like container, with an accompanying spring, valve, and stem.

However, the invention is not limited in all its aspects to the use of such replaceable containers 27. Instead, the polish may be contained directly in the receptacle 15, and other forms of fountain feed mechanisms 19 used for feeding polish automatically to the dauber pad 14 under firm pressure of the pad 14 onto a shoe by means of the hand of a person grasping the brush back 11.

Hence, it will be understood that the invention as hereinabove set forth is embodied in a particular form of construction but may be variously embodied within the scope of the following claims. Figure 4 is a modification in which an aperture 29' is in a top 28', and the spring abuts a container 27' proper, stem 24 passing through the aperture to project through ducts 20, 26.

I claim:

1. A combined shoe polish applicator and polisher brush comprising: a hand brush comprising a brush back providing a handle to be grasped in the hand, and a polishing pad at the base of the back; a dauber head integral with and forming an extension of said brush back; a dauber pad at the base of the dauber head integral with said polishing pad; a receptacle for polish in the upper part of the head having a removable lid and a discharge aperture in the bottom of said receptacle; an opening providing a duct in said dauber pad in communication with said aperture; and a fountain feed mechanism cooperatively as-

sociated with said dauber head, said fountain feed mechanism including a valve in said receptacle controlling the flow of polish through said discharge aperture, resilient means in said receptacle normally urging said valve to closed position, said valve including actuating means therefor projecting through said aperture and into said duct in said dauber pad, said actuating means terminating above the base of said dauber pad within said duct, whereby controlled amounts of polish may be automatically fed from the receptacle reservoir to the region of the dauber pad upon pressure of the dauber pad onto a shoe by the hand of a person grasping the brush back, for the purpose of feeding polish onto the shoe; and said dauber head and its pad being arranged at an angle to the brush back and its pad, whereby each lower brush or dauber surface clears the shoe surface when the other is applied to the shoe for its intended purpose.

2. A combined shoe polish applicator and polisher brush comprising: a hand brush comprising a brush back providing a handle to be grasped in the hand, and a polishing pad at the base of the back; a dauber head integral with and forming an extension of said brush back; a dauber pad at the base of the dauber head integral with said polishing pad; a receptacle for polish in the upper part of the head having a removable lid and a discharge aperture in the bottom of said receptacle; an opening providing a duct in said dauber pad in communication with said aperture; and fountain feed mechanism co-operatively associated with said dauber head, said fountain feed mechanism comprising a closed container for liquid polish removably positioned in said receptacle, said container having an outlet aperture therein in registry with said dis-

charge aperture, a valve in said container controlling the flow of polish through said outlet aperture, resilient means in said container normally urging said valve to closed position, said valve including actuating means therefor projecting through said outlet aperture and said discharge aperture into said duct in said dauber pad, said actuating means terminating above the base of said dauber pad within said duct, whereby controlled amounts of polish may be automatically fed to the region of the dauber pad upon pressure of the dauber pad onto a shoe by the hand of a person grasping the brush back for the purpose of feeding polish onto the shoe; and said dauber head and its pad being arranged at an angle to the brush back and its pad, whereby each lower brush or dauber surface clears the shoe surface when the other is being applied to the shoe for its intended purpose.
